Des. 228,971
Patented Oct. 30, 1973

228,971

ASH TRAY

Raymond Brodeur, 370 W. Sauve St.,
Montreal 357, Quebec, Canada

Filed May 22, 1972, Ser. No. 255,949

Term of patent 7 years

Int. Cl. D27—03

U.S. Cl. D85—2 H

FIG. 1

FIG. 2

FIG. 3

FIG. 4

FIG. 1 is a perspective view of an ash tray showing my new design;

FIG. 2 is a sectional view taken from the front;

FIG. 3 is a top plan view; and

FIG. 4 is a side elevational view with a portion of the tray cut away.

I claim:

The ornamental design for an ash tray, substantially as shown.
